UNITED STATES PATENT OFFICE

168,997

DISPLAY STAND

Sidney H. Horwitz, Shaker Heights, Ohio, assignor to The National Key Company, Cleveland, Ohio, a corporation of Ohio

Application November 7, 1952, Serial No. 22,189

Term of patent 14 years

(Cl. D80—9)

To all whom it may concern:

Be it known that I, Sidney H. Horwitz, a citizen of the United States and residing at Shaker Heights, in the county of Cuyahoga and State of Ohio, have invented a new, original, and ornamental Design for a Display Stand, of which the following is a specification, reference being had to the accompanying drawings, forming a part thereof.

In the drawings:

Fig. 1 is a perspective view of a display stand, showing my new design;

Fig. 2 is a top plan view; and

Fig. 3 is an elevational view thereof.

The dominant features of my design reside in the portions shown in full lines.

I claim:

The ornamental design for a display stand, substantially as shown and described.

SIDNEY H. HORWITZ.
